CLAIM

I claim the ornamental design for the sign with segmented indicators, as shown and described.

DESCRIPTION

FIG. 1 is a front view of the sign with segmented indicators showing my new design;

FIG. 2 is a top view of the sign with segmented indicators;

FIG. 3 is a bottom view of the sign with segmented indicators;

FIG. 4 is a right side view of the sign with segmented indicators;

FIG. 5 is a left side view of the sign with segmented indicators;

FIG. 6 is a rear view of the sign with segmented indicators; FIG. 7 is a front view of an alternative embodiment of the sign with segmented indicators showing certain segments in solid lines and certain segments in broken lines, FIGS. 2-6 show the respective top, bottom, right side, left side, and rear views of the embodiment shown in FIG. 7; and,

FIG. 8 is a perspective view of the embodiment of the sign shown in FIG. 7, the perspective view in FIG. 8 shows a perspective view of the embodiment shown in FIG. 1 aside from the configuration of the segmented indicators.

The broken lines in the FIGURES are for illustrating portions of the sign that form no part of the claimed design.
